Mitchell & Fairbanks,

Washing Machine.

Patented May 9, 1835.

John B. Mitchell & Sylvanus Fairbanks

Letters Patent.

The schedule referred to in these Letters Patent and making part of the same containing a description in the words of the said John B. Mitchell & Sylvanus Fairbanks thereby of their improvement in the Washing Machine and Cistern.

To all to whom these presents shall come —

Be it known that John B. Mitchell and Sylvanus Fairbanks of Readfield in the county of Kennebec and State of Maine, have invented a new and useful improvement in the washing machine and cistern, and that the following is a full and exact description of the construction and operation of the said machine, reference being had to the accompanying plate, fig 1. Represents one of the stocks, or flat blocks similar to those used in common fulling mills of a size suitable to the size of the machine to be constructed. A. is the stock or block flat on each side. B. is the standard attached thereto having a slot C. in the upper end sufficiently large to allow the ^{car} ~~cone~~ its proper play. Fig 2 is the shaft of the crank C. having two ^{car} ~~cone~~ D.D. attached to it, these cones are made of iron or steel or any other material suitable therefor and are placed upon the shaft in such a manner that their points are opposite to each other. Fig 3. is the machine in action, the stocks and cones are put into a frame having a top or cistern of a convenient size, (greater or smaller according to the wants of the operator) this cistern has a concave bottom so as to conform to the curve made by the stocks as they swing to and fro, and at the ends, a movable board is and placed at an angle with the horizon as represented by the dotted line H, by turning the crank C. the cones D.D. push them alternately one way and the other. There are two lids. I.I. which open toward the ends, on the under side of these lids we have attached flat boards so that the operator can finish any particular part of the clothes as wrist bands, collars, etc, that may not be washed clean by the usual pressure of the stocks. A portion of the clothes are put in at each end of the cistern, as in common fulling mills. At G. is a button having leather on the side next the cistern and service on

100-1
tightly, when you wish to empty out the water, you can push the button round and open the orifice and let the water escape.

Claims. What we specifically claim as our invention and for which we desire an exclusive right is 1. The application of cams, for pushing or putting into operation stocks for washing machine, fulling mill, tanners mill, for softening hide, &c. &c. 2. The application of the flat wash-board, to the lids of the washing machine as above described.

By testimony that the above is a true specification of our said improvement as above described, we have hereunto set our hands this day of March in the Year of our Lord 1835.
